UNITED STATES PATENT OFFICE.

WINFIELD S. GROVE, OF PHILADELPHIA, PENNSYLVANIA.

HANDLE FOR CHILDREN'S CARRIAGES.

SPECIFICATION forming part of Letters Patent No. 319,902, dated June 9, 1885.

Application filed December 6, 1884. (No model.)

To all whom it may concern:

Be it known that I, WINFIELD S. GROVE, a citizen of the United States, residing in the city and county of Philadelphia, State of Pennsylvania, have invented a new and useful Improvement in Handles for Children's Carriages, which improvement is fully set forth in the following specification and accompanying drawings, in which—

10 Figure 1 represents a rear view of a portion of a handle for a child's carriage embodying my invention. Fig. 2 represents a side elevation thereof.

Similar letters of reference indicate corresponding parts in both the figures.

15 My invention consists of means for attaching the side arms and cross-pieces of the handle of a child's carriage, whereby they are firmly and reliably connected, as will be hereinafter fully set forth.

20 Referring to the drawings, A represents the side arms, and B the cross-piece or grasping portion, of the handle of a child's carriage.

C represents sheet-metal eyes, each of the 25 form of an annulus, *a*, and legs *b*, parallel, or nearly so. The cross-piece B passes through the annulus *a*, and the side arms, A, are embraced on opposite sides by the legs *b*.

30 D represents bands or rings which encircle the legs *b*, and E represents lips on the ends of the legs as abutments for the bands D.

35 Screws *c* are passed through the band D and legs *b* into the side arms, A, and the legs may also be secured to said arms by screws *d* independent of the screws *c*.

It will be seen that the eyes firmly connect

the side arms and cross-bar of the handle, and as said eyes are formed of sheet metal they may be strained on the parts they embrace, and thus draw the same tightly together. 40

The bands D also encircle the legs and retain the same in position, preventing separation thereof, and longitudinal draft on the legs is restrained by the lips E, which, having the securely-connected bands abutting against the 45 same, serve to increase the security of connection of the legs with the side arms, the effect of which is a strong and durable attachment of the cross-bar with the side arms.

Having thus described my invention, what I 50 claim as new, and desire to secure by Letters Patent, is—

1. A handle of a child's carriage, in combination with eyes formed with parallel legs connecting the side arms and cross-bar of said 55 handle, and bands encircling said legs, substantially as and for the purpose set forth.

2. A handle of a child's carriage, in combination with eyes formed with parallel legs connecting the side arms and cross-bar of said 60 handle, and bands encircling said legs, the ends of the legs being formed with lips, substantially as and for the purpose set forth.

3. The cross-bar B, in combination with sheet-metal eyes C, said eyes having an annulus, *a*, parallel legs *b*, and lips E, side arms, A, and band D, substantially as and for the purpose set forth. 65

WINFIELD S. GROVE.
